J. LYALL.

CARPET.

No. 16,384.

Patented Nov. 17, 1885.

UNITED STATES PATENT OFFICE.

JAMES LYALL, OF NEW YORK, N. Y.

DESIGN FOR A CARPET.

SPECIFICATION forming part of Design No. 16,384, dated November 17, 1885.

Application filed June 25, 1885. Serial No. 469,775. Term of patent 7 years.

To all whom it may concern:

Be it known that I, JAMES LYALL, of the city and State of New York, have invented and produced a new and original Design for 5 Carpets, of which the following is a specification.

This design is represented in the accompanying photograph.

The prominent features of this design are 10 the stripes A A, composed of checks, the lines upon every alternate check running diagonally in one direction and the lines upon the other checks running diagonally in the other direction, and the intermediate narrower stripes, 15 B B, also checkered and traversed by narrower bands, as represented in the photograph. The stripe C, composed of checks, is the same as the stripe A, except the peculiarity of effect resulting from the irregular narrow stripes by 20 which it is traversed, and by differences in colors.

I claim as my invention—

1. The design for carpets, consisting of the stripes A A, composed of checks having diagonal lines in alternate directions, and the 25 narrower checkered stripes B B, traversed each centrally by a narrower stripe, as shown in the photograph.

2. The design for carpets, consisting of the stripes A A, composed of checks having diagonal lines in alternate directions, the narrower checkered stripes B B, traversed each centrally by a narrower stripe, and the stripes C, composed of checks and traversed by numerous irregular narrow stripes, as shown in 35 the photograph.

Signed by me this 19th day of June, A. D. 1885.

JAMES LYALL.
